UNITED STATES PATENT OFFICE

G. B. SHAFFER, OF DELTA, OHIO.

IMPROVEMENT IN GRAIN-BINDERS.

Specification forming part of Letters Patent No. **88,087**, dated March 23, 1869.

To all whom it may concern:

Be it known that I, G. B. SHAFFER, of Delta, in the county of Fulton and State of Ohio, have invented a new and useful Improvement in Grain-Binding Machines; and I do hereby declare that the following is a full, clear, and exact description thereof, which will enable others skilled in the art to make and use the same, reference being had to the drawings, forming part of this specification.

This invention relates to improvements in grain-binding attachments for reaping-machines, whereby it is designed to provide an attachment, the moving parts of which may be operated from the driving-gear of the reaper to bind up the bundles of grain as they are delivered to it, and discharge them when so bound, all as will be more fully described hereinafter, on reference to the accompanying drawings, wherein—

Figure 1 represents a plan view of my improved machine. Fig. 2 represents a transverse sectional elevation on the line *x x*, Fig. 1, and Figs. 3 to 9 represent detail views.

Similar letters of reference indicate like parts.

The attachment is designed to be secured to the framing of a reaping-machine in such a manner that the receiver A will be adapted to receive the bundles of grain as they are delivered by the rakes from the apron of the machine. The arrangement which I prefer is to so attach it that the end A¹ will be presented in the direction in which the machine moves, and directly behind the driving-wheels, so that the receiver will take the grain from the near or left side of the said apron, and whereby a platform or seat may be provided for the attendant, who directs the operations of the machine by means of the hand-crank A² A³, and forces the bundles to the bottom of the receiver, and compresses them as much as possible previous to the winding of the binding-cord around them by the hand-crank A⁴, to which the compressing-arm A⁵ is attached. The binding-cord B is supplied from a spool, B¹, arranged in suitable brackets, and carried through the axis of the shaft B², and over suitable guide-pulleys to the winding-head B³, supported on a bent arm projecting from the

inner end of the shaft B². C represents another winding-head, provided with a roller, C¹, having pins projecting from its periphery, which is so geared with reference to the winding-head B³ and otherwise arranged as to be caused to move into the path of the said head B³ and in contact therewith as it is moved around the bundle lying in the receiver A. The face of the carrying-head B³ is provided with a ridge or projection *b*, through which the cord projects, also with groove *b*¹ and *b*² and a curved guide, *b*³.

When the said winding-heads approach each other they meet in the direction represented by the arrow *b*⁴, the pin C¹ standing in the direction indicated at C², entering the groove *b*¹ of the head B³, while the end C³ of the head C enters the curved groove of the same, and the curved projection *b* enters the space C⁴, between the wheel C¹ and the end C³ of the head C. As the two heads thus engaged continue in their respective courses past each other, the end of the cord B, projecting through one of the holes shown in the projection *b*, will be drawn into the space C⁴, and the wheel C¹ will be turned around by the action of the wall of the inclined groove *b*¹, so as to loop the cord around or past a pin, C⁵, Fig. 6, and cause it to assume the position represented at C⁶, Fig. 7, which will hold the cord with sufficient power to enable the head C to retain it and carry it around the loopers, as will presently appear, while the other winding-head B³ is delivering the cord around the bundle. As the wall of the groove *b*¹ will not turn the wheel C¹ fully into the desired position for holding the cord, as represented in Fig. 7, another groove, *b*², and a curved guide, *b*⁴, are provided in the head B³ under such an arrangement as to receive the next pin of the wheel C¹ succeeding the one being acted on by the wall of the groove *b*¹, and in a similar manner effect the full movement of the said wheel C¹.

These winding or carrying heads are operated from the driving-shaft D, which is common to both, the one B³ through the wheels D¹, D², and D³, and carries the yarn around the bundle after having delivered the end to the head C, as above described; and the other,

C, through the wheels D⁴, D⁵, and D⁶, and winds the yarn around the loopers E, and it is so arranged that it is capable of sliding parallel with its axis of motion, and is provided with a lever, E¹, taking into a groove in its hub, for giving the said sliding motion, the said lever being vibrated by a grooved cam-wheel, E², on the shaft of the wheel D⁵. The groove in the said cam-wheel is so formed that it will cause the sliding head C to recede sufficiently after having taken hold of the yarn to allow it to wind the yarn on the loopers through one revolution, and at the beginning of the second revolution to pass up to the head B³, coming into contact with it, taking hold of the yarn a second time and winding the yarn for a part of the said revolution on the projecting end of the shaft E³, which is provided with a pin, E⁴, for the purpose of hooking the yarn so wound on it and drawing it within the loop formed on the loopers E, and which is discharged therefrom over the part drawn in by the recession of the rod E³, which simultaneously turns the points of the loopers E down against the said shaft to discharge the said loop.

The recession of the said shaft is effected by a spring, E⁵, when the lever which, by the action of the cam E⁷, moves the shaft in the opposite direction has arrived at the notch in the cam which permits the said spring to act.

Before the winding-head C has completed its second revolution and is so thrown forward as to come into contact with the head B³ and take another hold of the cord, the latter is then severed at the head B³ by the knife e, the operation of which will be presently described. The said head C now holds both ends of the cord, which it winds onto the shaft E³ just previous to its recession, which effects the tying of the knot, as before described.

The said ends are disconnected from the carrying-head C by a knife, F, on the said head, which is actuated at the proper moment by the shank F¹ thereof coming into contact with the fixed arm F².

The cutter e, which severs the yarn from the head B³, is supported on a sliding shank, e¹, which is set into motion at the proper time, immediately after having delivered the yarn to the head C, the second time by the curved bell-crank e², pivoted to the frame below the wheel D², which is provided with a lug, e⁴, which comes in contact with one end of the bell-crank e² and moves it in the direction to operate the knife e. After its operation the said knife is retracted by a spring, e⁵.

The driving-wheels D¹ and D⁴ are fixed loosely upon the driving-shaft D, and provided with clutches connected by suitable bell-cranks to the stop-levers C¹, arranged to spring into notches in the disks C², to stop the movements of the winding-heads at the proper point. The said stop-levers are also connected by suitable links to the hand-cranks A² and A³, by

which the operator raises them out of connection with the notches in the said disks, and at the same time slides the clutches G into gear with the wheels D¹ and D⁴, setting them into motion, the driving-shaft D being always in motion.

To effect the discharge of the bundle after it is thus bound from the receiver, the latter is made in two parts, the lowermost A⁴ being hinged at A⁵, and provided with a balance-weight, A⁶, which will restore it to the closed position after discharging a bundle. It is also provided with a sliding catch, which takes under a projection of the strengthening-rib H¹, as represented in dotted lines in Fig. 1, and holds it up under the weight of the bundle until the movement of the recession of the lever E⁶, which strikes an elbow H² of the said slide and withdraws it from under the said lug, allowing the said swinging part of the receiver to fall at the moment that the knot is tied in the yarn, when the operator may cause the necessary movement of the follower I in the receiver by the hand-crank I¹ to eject the bundle, the said hand-crank being arranged in connection with said follower by means of a chain or spring, I², and a piston, I³.

Having thus fully described my invention, I claim as new and desire to secure by Letters Patent—

1. The winding-head B³, constructed and arranged substantially as and for the purpose specified.
2. The combination with the same of the cutter e, arranged and operated substantially as and for the purpose specified.
3. The winding-head C, provided with the roller C¹, and otherwise arranged substantially as and for the purpose specified.
4. The combination of the winding-heads B³ and C, when arranged to operate together, substantially as and for the purpose specified.
5. The combination with the winding-head C of the cutter F, arranged and operated substantially as and for the purpose specified.
6. The loopers E, adapted to receive the yarn upon their hooked ends to form a loop, through which the pin E⁴ upon the rod E³ draws the yarn as said rod is receded by the spring E⁵, all constructed and arranged as described, for the purpose specified.
7. The combination with the loopers E of the rod E³, arranged as described, and provided with the hook E⁴, substantially as and for the purpose specified.
8. The combination with the loopers E and the hooked rod E⁴ of the winding-head C, substantially as and for the purpose specified.
9. The combination of the winding-heads B³ and C and the loopers E and hooked shaft, substantially as and for the purpose specified.
10. The receiver A, constructed of two parts and hinged together as described, and provided with the balance-weight A⁶ and

plunger I, substantially as and for the purpose described.

11. The combination, with the winding-heads B³ C and the looping-apparatus, of the receiver, substantially as and for the purpose described.

12. The arrangement of the stop-levers G¹, disks G², and clutches G, and hand-cranks A²

and A³, substantially as and for the purpose specified.

The above specification of my invention signed by me this 10th day of October, 1868.
